United States Patent Office.

EDWARD C. MOORE, OF YONKERS, NEW YORK, ASSIGNOR TO TIFFANY & CO., OF NEW YORK CITY.

Design No. 4,476, dated November 15, 1870.

DESIGN FOR SPOON AND FORK-HANDLES.

The Schedule referred to in these Letters Patent and making part of the same.

I, EDWARD C. MOORE, of Yonkers, Westchester county, New York, have invented and produced a new and original Design for Handles of Spoons, Forks, &c., of which the following is a specification.

My design consists of features clearly set forth in the accompanying illustration and following description.

Figure 1 is a view of the upper side or front of the handle of the spoon or fork, and

Figure 2, of the under side or back of the same.

A fillet or rounded edge extends around the handle. It is made wide at the top, *a*, and tapers into a thread at and down the shank, terminating at the bowl or fork portion, into which it is merged.

At a point, *b*, at the base of the bowl, an inner thread commences with a scroll, and extends up each side of the shank, expanding and coinciding with the form of the handle, and terminating in symmetrical spiral scrolls, as at *c*.

It commences again as part of a symmetrical-pointed leaf situated midway on each side of the handle,

and extends to the top *a*, inclosing two rosettes, from which a bold ornament of a honeysuckle pattern depends. Below this, and immediately above and below the spiral scrolls, are ornaments of a corresponding character.

The back of the handle is substantially the same, except that the ornament of a honeysuckle pattern is omitted, leaving the space *d* as a shield inclosed by the thread and fillet; and where the shank expands into the spoon or fork, at *e*, there is added a pointed leaf and shell ornament.

Claim.

I claim—

The design for a handle for spoons and forks, substantially as described and illustrated by the accompanying drawing.

E. C. MOORE.
